Robert C. Ware, 1065 Kingston Drive, Olean, N.Y.

Filed Mar. 13, 1962, Ser. No. 69,248

Term of patent 14 years

(Cl. D81—10)

FIG. 1.

FIG. 2.

FIG. 3.

FIG. 1 is a perspective view of a baseboard heater casing, showing my new design.

FIG. 2 is an enlarged perspective view of a portion of the grill at the top and front thereof.

FIG. 3 is an enlarged fragmentary view showing the knob thereof in perspective.

The end not shown is substantially the same as that shown in FIG. 1. The rear is substantially closed and plain.

I claim:

The ornamental design for a baseboard heater casing, substantially as shown and described.
